LESTER L. JONES, OF ORADELL, NEW JERSEY.

VARIABLE CAPACITOR.

Application filed December 13, 1923. Serial No. 680,465.

This invention relates to a variable condenser, and more particularly to a variable compensating condenser in which there are provided two variable capacities variable in inverse ratio; and has special reference to the provision of a compensator condenser especially designed for use in a radio receiving system of the type disclosed in my copending application for "Capacitive coupling control system," Serial No. 607,046, filed Dec. 15, 1922, the present application being a division and continuation in part of the said copending application.

The principal objects of my present invention include the provision of a variable compensating condenser designed for employment with relay or amplifier tube circuits in which the feed back of energy from the output to the input circuit due to the unavoidable capacitive coupling between the circuits is desired to be compensated or neutralized; the further provision of a compensating condenser of this nature which is made adjustable to adapt the same to different makes or types of relay or amplifier tubes, and which is provided with means for preventing the detuning of the input circuit during condenser adjustment; the still further provision of a condenser of this nature in which the elements that are adapted for connection to high potential points of the receiving circuit are electrostatically shielded, and in which furthermore the parts are so inter-related that in spite of the very low capacity values of the condenser (of the order of 10 m. m. f.'s) adjustment is unaffected by the hands or body of the operator or user in obtaining a setting of the same.

To the accomplishment of the foregoing and such other objects as may hereinafter appear, my invention consists in the elements and their relation one to the other, as hereinafter particularly described and sought to be defined in the claims, reference being had to the accompanying drawings which show preferred embodiments of my invention, and in which:—

Fig. 1 is a view taken in cross-section of one form of my compensator condenser,

Fig. 2 is a cross-sectional view of a modification thereof,

Fig. 3 is a view taken in cross-section on the line 3—3, Fig. 2,

Fig. 4 is a perspective view showing the parts detached and the manner of assembling the same, and

Fig. 5 is a diagram of a relay or amplifying circuit showing my invention applied thereto.

Referring first to Fig. 5 of the drawings, I show an amplifier or relay tube circuit system for exemplifying a contemplated mode of application or use of my invention. The relay tube system comprises an electron discharge or thermionic relay including the filament 10 which is heated to incandescence by the battery 11 connected thereto for producing the electron stream, the controlling grid 12 and the controlled plate 13, the grid being connected to a controlling or input circuit *i* and the plate being connected to a controlled or output circuit *o*.

The input circuit is provided as usual with an inductor 14 which may be coupled for energy reception to an induction coil of an antennæ circuit and a variable condenser 15 connected in parallel to the inductor 14, the condenser being adjustable, as is well known, for varying the tuning characteristics or period of the input circuit to syntonize the same to the desired incoming frequency, the said inductor and condenser being connected to the grid or high potential side of the input circuit and to the filament by means of the conductors 16 and 17 respectively.

The output circuit *o* is provided with an external or output impedance 18 connected at one end by means of a conductor 19 to the plate 13 and connected at the other end by means of the conductor 20 to the positive terminal of the battery 21, the negative terminal of which is connected to the filament 10, as clearly shown in the drawings. The output impedance 18 may as shown comprise the primary of a transformer and is coupled to a secondary (not shown), the said secondary receiving the amplified energy for rectification or further amplification if desired.

As explained in the above mentioned parent application, due to the normal unshielded capacity between the plate 13 and the grid 12 of the electron discharge tube, some of the energy in the output circuit is objectionably retransferred or fed back to the input circuit, the grid 12 being charged by the plate 13 through the capacity therebetween. For compensating for this feed back to reduce or entirely eliminate the effect of the same, I provide means for neutralizing in part or in whole the charge carried from

the plate to the grid. This result I accomplish by providing means for impressing on the grid 12 a charge which may be less than, equal to, or greater than in magnitude but opposite in sign to the charge carried thereto from the plate; and to this end I provide means for creating a potential opposite to the potential on the plate and impressing the said potential on a capacity means connected to the grid 12. Where feed back is desired to be entirely eliminated, the product of the said potential and the capacity is made equal to the charge transferred to the grid from the output circuit.

15 For creating the opposite potential, I provide an additional impedance 23 comprising a coil wound in the same direction as the output impedance coil 18 closely coupled to the same and having a number of turns

20 preferably equal to the number of turns in the winding 18, the said additional impedance being connected at one end to the conductor 20 and at its other end by means of a conductor 24 to a condenser 25 which is

25 connected as shown to the high potential side of the input circuit by means of a conductor 26, the said condenser being preferably made equal to the capacity between the grid and the plate and the capacity between the conductors or leads connected thereto (of the order of 6 m. m. f.'s for present-day receiving tubes). By creating a potential opposite in sign to the potential on the plate

30 13 and by impressing the same on the condenser 25, it will be apparent that the grid 12 is supplied with an electric charge which is equal and opposite to the charge fed back thereto from the plate 13, this equalization or neutralization of the charge preventing

35 40 the setting up of objectionable local oscillations in the input circuit.

For the purpose of adjusting the compensating effect to adapt the same to different relay tubes, the internal capacities of which vary, and to the capacity of the leads which may vary in different receiving sets, the condenser 25 is made variable; and to this end includes a movable plate or element *a* and a stator plate or element *c*, the former being movable with respect to the latter in opposite directions, as indicated by the arrows in Fig. 5.

In view of the negligible impedance of the coil 23 as compared with the impedance of the grid coil 14, the change of capacity between the plates *a* and *c* during adjustment is normally effective for modifying the capacity of the grid circuit and hence the period of the same. For the purpose of preventing this variation of capacity of the condenser from varying the tuning characteristics or period of the grid or input circuit, I have found it desirable to provide means for varying the capacity of the input circuit simultaneously and inversely in

correspondence with the varying of the capacity of the equalizing circuit. To this end the condenser 25 includes a third and stator plate or element *b* connected to the filament side of the input circuit by means of a conductor 27, said filament side of the circuit being preferably grounded as shown at 28, the stator plate *b* being related to the plates or elements *a* and *c* so as to provide a plurality of plate sets *ac* and *ab*, movement of the common plate being effective for varying the capacity of one plate set inversely with respect to the other plate set. By the provision of this construction it will be seen that the effective grid circuit capacity may be maintained constant during adjustment of the condenser plate *a* so that the tuning or period of the grid or input circuit is maintained.

The three-plate condenser of my invention may constructionally take the form shown in Fig. 1 of the drawings, in which the three plates comprise cylinders or tubes *a'*, *b'* and *c'*, the tubes *b'* and *c'* being fixed or stationary and forming the stator element and the tube *a'* being telescopically movable in opposite directions between the tubes *b'* and *c'* and forming the movable element. The tube *a'* is provided with a connecting means 29 for connection to the high potential side of the grid circuit, the tube *b'* is provided with a connecting means 30 for connection to the filament and ground end of the circuit, and the filament *c'* is similarly provided with a connecting means 31 for connection to the impedance of the equalizing circuit.

The tube *b'* may be fixedly carried by a collar 32, the said collar being threadedly received by a threaded bushing 33 which is stationarily mounted on a panel board 34, the panel board being secured between the shoulder 35 of the bushing 33 and the collar 32. Fitting within the tube *b'*, I provide a tube of insulating material 36 such as hard rubber on which the tube *c'* is fixed by means of the connecting element 31, the tube *a'* being constructed to telescopically slide in the tube of insulating material.

For moving the plate element *a'*, there is provided the shaft or spindle 37 made of electrically conductive material which is threaded the greater part of its length as shown at 38 for threaded engagement with a tapped member 39 fixedly carried by an insulating dial member 40 which carries a pointer 41. The shaft is longitudinally recessed as at 42 for receiving a pin 43 fitted into the bushing 35, this to the end of constraining the shaft to move axially only upon rotation of the dial 40. With this construction it will be obvious that upon rotation of the dial in opposite directions the shaft and the condenser tube or plate *a'* will be moved in opposite directions for

varying the capacities of the plate sets in inverse ratio.

Since the movable element a' is designed for connection to the high potential side of the grid circuit, means is provided for insulatably carrying the same on the shaft 37, and to this end the plate or element a' is fixed to a member 44 made of insulating material; the said member being fixedly attached to the shaft 37 as by being threaded thereto, as shown in the drawings. For shielding the high potential elements of the condenser from the hand of the operator, the shaft 37 is conductively connected to the stator plate b' which is to be connected to ground, the conductive connection being provided by making the parts 32, 33, 35 and 39 of electrically conductive material. With this arrangement the plate b' provides a ground shield for the condenser elements a', c' .

Referring now to Figs. 2 to 4 of the drawings, I show a modification of my compensator condenser in which the adjustment from maximum capacity of one plate set to maximum capacity of another plate set is obtained through a half-revolution of the operating shaft. In this construction the movable element a^2 is carried by an insulating body 30 or plate 44' fixed to the metallic shaft 37' and the stator elements b^2 and c^2 are fixedly attached to an insulating plate or body 45, the said plate a^2 being provided with the connecting means 29' and the plates b^2 and c^2 being provided respectively with the connecting means 30' and 31', a sheet of dielectric material 36' being arranged between the stator and movable plates. For limiting the movement of the rotor plate with respect to the stator plate, I provide the two stop pins 46 carried by the insulating body 45 and the complementary stop pin 47 carried by the insulating body 44', the sheet of dielectric material 36' being provided with a slot 48 through which the pin 47 projects, as clearly shown in Fig. 2 of the drawings.

For shielding the high potential elements of the condenser in the form of construction shown in Figs. 2 to 4 of the drawings and for connecting the shaft 37' to ground, I provide a separate electrostatic shield 48 which forms a carrier for the parts of the condenser, the said shield being connected to the ground plate b^2 by means of the securing element 49, the shield plate 48 being cut or stamped out of sheet metal in a manner to provide the spring fingers 49', 49'', the lower ends of which surround and engage the shaft 37', as clearly shown in Fig. 3 of the drawing. By means of this construction it will be evident that when the plate b^2 is grounded, the shaft 37' and the shield plate 48 are both at ground potential. In mounting this compensator condenser on a support or panel 34', the dial 40' is secured

to the shaft 37' and a spring washer 50 is inserted between the panel and the dial to hold the condenser plates in properly spaced relation.

The manner of constructing and using my compensator condenser will in the main be apparent from the above detailed description thereof and the mode of application of the same. It will be further apparent that while I have shown the compensator condenser in the preferred forms, that numerous changes may be made therein without departing from the spirit or principle of the invention. It will be obvious, for example, that while I prefer to provide a single condenser element in the rotor common to both condenser plate sets, that this may be varied in many ways to accomplish the same result. It will be also obvious that the parts may be re-arranged without departing from the essence of the invention defined in the following claims.

I claim:

1. A variable condenser comprising a plurality of plate sets including two independent stator elements, a movable element capacitively related to both stator elements and a shaft insulatably carrying the movable element and conductively connected to one of said stator elements.

2. A variable condenser comprising a plurality of plate sets including two stators and a rotor common to the stators, rotation of the rotor being effective for varying the capacity of one plate set inversely with respect to the other, and a shaft made of an electrically conductive material insulatably carrying the rotor and conductively connected to one of the stators.

3. A variable condenser comprising a plurality of plate sets including relatively movable elements, and means for moving the movable element to vary the capacity of one plate set inversely with respect to the other plate set, said means including an electrically conducting shaft insulatably carrying the movable element and conductively connected to a stationary element.

4. A variable condenser comprising a plurality of plate sets including two stator plates and a rotor plate arranged so that when rotated through a half revolution the capacity between the plates will be varied from maximum capacity of one plate set to maximum capacity of another plate set, and a shaft insulatably carrying the rotor element and conductively connected to one of the stator elements.

5. A variable condenser comprising a plurality of plate sets including relatively movable elements, a shaft insulatably carrying the movable element, and an electrostatic shield conductively connected to said shaft and to a stationary element.

6. A variable condenser comprising a plu-

- rality of plate sets including two stator elements, a movable element, a shaft made of an electrically conductive material insulatably carrying the movable element and an electrostatic shield conductively connected to said shaft.
7. A variable condenser comprising a plurality of plate sets including two stator elements, a movable element, a shaft made of an electrically conductive material insulatably carrying the movable element and an electrostatic shield conductively connected to said shaft and to one of said stator elements.
8. A variable condenser comprising a plurality of plate sets including relatively movable elements, a shaft insulatably carrying the movable element, and an electrostatic shield conductively connected to said shaft.
9. A variable condenser comprising a pair of independent stator plates, a rotor plate common to the stator plates, a conducting shaft insulatably carrying the rotor

plate and a stationary electrostatic shield conductively connected to the shaft.

10. A variable condenser comprising a pair of independent stator plates, a rotor plate common to the stator plates, a conducting shaft insulatably carrying the rotor plate and a stationary electrostatic shield conductively connected to the shaft and to one of said stator plates.

11. A variable condenser comprising a plurality of plate sets including relatively movable elements and means for operating the elements to vary the capacity of one plate set inversely with respect to the other plate set, and an electrostatic shield conductively connected to a stationary element of said plate sets.

Signed at New York city in the county of New York and State of New York, this 8th day of December, A. D. 1923.

LESTER L. JONES.
